Primary Examiner — Cathron Brooks*Assistant Examiner* — Daniel J Domino(74) *Attorney, Agent, or Firm* — Oblon, McClelland, Maier & Neustadt, L.L.P.(57) **CLAIM**

The ornamental design for a display screen or portion thereof with graphical user interface, as shown and described.

DESCRIPTION

FIG. 1 is a front view of a first embodiment of a display screen or portion thereof with graphical user interface;

FIG. 2 is a second embodiment thereof; and,

FIG. 3 is a third embodiment thereof.

The broken line showing of a display screen and elements within the graphical user interface including text, numbers and symbols is included for the purpose of illustrating portions of the article of manufacture, and forms no part of the claimed design.
